UNITED STATES PATENT OFFICE.

JULIUS BING, OF EISENACH, GERMANY, ASSIGNOR TO MAGNET-WERK G. M. B. H. EISENACH SPEZIALFABRIK FÜR ELECTROMAGNET APPARATE, OF EISENACH, GERMANY.

MAGNETIC CHUCK.

Application filed March 26, 1925, Serial No. 18,584, and in Germany September 27, 1924.

My invention relates to improvements in magnetic work holding apparatus and it particularly has reference to round electromagnetic chucks.

5 The known round magnetic chucks having a surface plate subdivided into a number of fields of different polarity have the great disadvantage, that the separating gaps between the separate pole fields lie very far apart so that only relatively large pieces of work can be attached. The greater the subdivision into different poles of the plate, the smaller can the pieces of work be, which are to be mounted on the plate, and the greater 10 can the number of such pieces be. In rectangular chucks, the face plate may be very finely subdivided by laying alternate narrow strips of brass and iron next to one another and bolting the strips together. It would 15 be very difficult to adapt this method of construction to round chucks as in this case the surface plate would have to consist of separate alternate rings of brass and iron, the fitting together of which would necessitate 20 very accurate work and take a considerable amount of time, more particularly as it is important for the rings to fit as closely together as possible.

25 According to my invention these and other difficulties are overcome by the pole plate being constructed by winding two metal strips, a magnetic and a non-magnetic one, in the form of a spiral. Further features and objects of my invention will more clearly appear from the following specification having reference to the accompanying drawing showing by way of exemplification a preferred embodiment of the principles of my invention. In said drawing

30 Fig. 1 is an axial section and

35 Fig. 2 is a front view of the upper plate of a chuck constructed according to the invention.

40 The chuck shown comprises in the usual manner a dished magnet part 1 with the winding 2 and the pole plate 3. The latter is made by winding a strip 5 of brass and a strip 6 of iron together in the form of a spiral around a circular core piece 4 made of iron. In order to cause the separate windings to fit as closely together as possible the strips may be wound on under considerable

tension and may if necessary be heated. After they have been wound on, the ends of the strips are fixed, for instance by soldering, after which the wound disc may be turned off on its faces and periphery. The disc is surrounded by a ring 7 of iron, for instance by shrinking the latter on. In winding the two metal strips insulating metal and packing material may be placed between the separate windings. The top plate made in this way is then placed on the magnet part 1 in the usual manner and attached to it by screws or the like.

In the manner described a pole plate of any desired degree of subdivision may be made with a relatively small amount of work and at very small cost.

I claim:—

1. A pole plate for magnetic work holding apparatus, comprising at least two spirals inserted one within the other of alternate strips of magnetic and non-magnetic metal, and a metal ring surrounding said spirals.

2. A pole plate for magnetic chucks, comprising a metal core piece, a disc-shaped body surrounding said core piece, and being formed of two spirals inserted one within the other of strips of magnetic and non-magnetic metal, and a closed metal ring surrounding said disc-shaped body.

3. A pole plate for magnetic chucks, comprising a core piece of magnetic metal, an iron strip spiral surrounding said core piece and having its convolutions spaced apart from one another, a non-magnetic metal strip spiral disposed within the spaces between the convolutions of said iron strip spiral, said spirals closely secured one to the other.

4. A pole plate for magnetic chucks, comprising a core piece of magnetic metal, an iron strip spiral surrounding said core piece and having its convolutions spaced apart from one another, a brass strip spiral disposed within the spaces between the convolutions of said iron strip spiral, said spirals closely secured one to the other, and a closed iron ring surrounding said spirals.

In testimony whereof I affix my signature.

JULIUS BING.
